ATTORNEY.

UNITED STATES PATENT OFFICE.

BERNARD McGINTY, OF DOYLESTOWN, PENNSYLVANIA, ASSIGNOR TO PRINTERS SPECIALTIES COMPANY, A CORPORATION OF DELAWARE.

ROLLER-TRUCK.

1,097,762.

Specification of Letters Patent.

Patented May 26, 1914.

Application filed April 3, 1912. Serial No. 688,134.

To all whom it may concern:

Be it known that I, BERNARD McGINTY, a citizen of the United States, residing at Doylestown, in the county of Bucks and 5 State of Pennsylvania, have invented certain Improvements in Roller-Trucks, of which the following is a specification.

My invention relates to roller trucks for printing presses and its object is to provide 10 means for varying the effective radius of the trucks to secure the desired action of the rollers by which the ink is distributed to the type, plate or other medium used in printing.

15 In the presses generally used, the elastic inking rollers change in diameter, due to atmospheric and other conditions, with the result that their pressure upon the type and the amount of ink applied thereto varies so 20 that too little or too much ink is frequently applied with corresponding undesirable results in the work produced. Again, it frequently happens that it is desired to obtain a particular effect dependent upon a particu- 25 lar degree of pressure of the rollers upon the type, which cannot be effected without considerable difficulty or at all by the usual rollers and trucks.

By my improved means, I am enabled to 30 overcome the foregoing defects and attain improved effects.

The nature and characteristic features of 35 my invention are fully disclosed in the following description and the accompanying drawings in illustration thereof.

In the drawings, Figure 1 is a transverse sectional view of a type bed containing a frame, in combination with a roller having trucks supported by the tracks at the sides 40 of the bed; Fig. 2 is an enlarged view of the end of a roller with my improved truck shown in section; Fig. 3 is a sectional view of a part of a truck of modified form; Fig. 4 is an axial view showing the interior of 45 the truck cup viewed in section in Fig. 2; and Fig. 5 is a side elevation of a part of a printing press illustrating the application of my improvements.

As illustrated in the drawings, the bed 1, 50 which contains the type form 2, has the tracks 3 at the sides thereof, in combination with elastic inking rollers 4 provided with trucks 5 which travel upon the tracks in the

operation of moving the rollers over the disk 6 and the type contained in the form 2. 55

My trucks 5 comprise the cylindrical truck bodies 5^a which are sleeved on the bearings 4^a of the rollers 4, the parts 5^a having the longitudinal channel 5^b and the bearings 4^a having the keys 4^b engaged therein whereby 60 the parts are held together. The bodies 5^a are adapted to act directly on the tracks 3 in a usual manner in case of extreme contraction of the rollers or the necessity for extreme pressure thereby. 65

As illustrated in Figs. 2 and 4, a cup 5^c is sleeved on the body 5^a (with which it makes a close fit) to provide a truck of the effective diameter desired. This cup comprises the cylindrical part 5', which fits upon 70 the periphery of the body 5^a, and the web 5" having the key 5"" turned in therefrom, the key being engaged in the channel 5^b.

Fig. 3 illustrates a modified truck having the body 7^a with a conical periphery, in 75 combination with a cup 7^c which forms a taper fit therewith, whereby such cup can be held in place, either with or without the key 7"" for engaging the channel 7^b. While the engaging conical surfaces have been 80 shown with a marked inclination to the axis for the purpose of pointing out the relation distinctly, in practice such inclination is comparatively slight.

It is to be understood that in practice cups 85 are provided of various outer diameters, which will permit the effective working diameters to be varied, say two, four or six points, as may be required by the particular operation in hand. 90

Having described my invention, I claim:

A truck for a printing press roller comprising a body having a bearing through which it supports said roller, and a cup comprising a band engaging the periphery 95 of said body, a web extending transversely to and integral with said band, and a lug projecting from said web whereby said cup is fixed relatively to said body.

In witness whereof I have hereunto set my 100 name this 29th day of March, 1912, in the presence of the subscribing witnesses.

BERNARD McGINTY.
